UNITED STATES PATENT OFFICE.

CLAUDE E. MENTZER, OF DES MOINES, IOWA.

SPIDER-WEB-LIGHT-RAY CONTROL DEVICE.

Application filed September 27, 1921. Serial No. 503,558.

To all whom it may concern:

Be it known that I, CLAUDE E. MENTZER, a citizen of the United States, and a resident of Des Moines, in the county of Polk and 5 State of Iowa, have invented a certain new and useful Spider-Web-Light-Ray Control Device, of which the following is a specification.

The object of my invention is to provide a 10 device for controlling the rays of light from a lamp used on automobiles or the like, properly directing and diffusing the light rays.

It is well-known that in some sections of 15 the country, laws have been passed requiring lamps on automobiles to be so arranged that the rays are directed downwardly and forwardly.

It is my object to provide a device, which 20 can be made at a very low price and of extremely simple construction, whereby the proper deflection of the light rays can be accurately and properly secured.

Still another object is to provide a series 25 of strips curved from end to end so as to form an incomplete circle, the strips being inclined from front to rear, so that the light rays will be restricted and shot downwardly when passing between the strips.

Still another object is to provide a means 30 for securing a number of strips together for holding them in proper position relative to each other, and means for securing the assembled strips into the lamp housing in such a manner, as the strips will be slightly 35 inclined from front to rear.

With these and other objects in view, my 40 invention consists in the construction, arrangement and combination of the various parts of my device, whereby the objects contemplated are attained, as hereinafter more fully set forth, pointed out in my claim, and illustrated in the accompanying drawings, in which:

Figure 1 is a central, sectional view taken 45 through a lamp housing with a device embodying my invention installed therein; and

Figure 2 is an enlarged, detail, sectional view, showing the spring clip for holding 50 the strips inclined from front to rear.

In the accompanying drawings, I have used the reference numeral 10 to indicate generally a lamp housing or casing, which is provided with a reflector 11. A lamp bulb 55 12 is provided in the ordinary manner.

An annular band or ring 13, having a

flange 13^a thereon is provided. The ring 13 engages the edge of the lamp housing 10. A lens 14 is received on the inside of the ring 13 and rests against the flange 13^a. 60

In order to securely hold my improved light deflector in proper position, I provide a ring 15 preferably made of stiff wire. The ring 15 is received between the lens 14 and the edge of the reflector 11, as clearly 65 illustrated in Figure 1 of the drawings.

A number of wires 17 have their ends secured to the ring 15 equi-distant from each other in the manner hereinafter described 70 and have their centers crossing each other.

Received on the wires 17 are a series of spaced strips 18, 19, 20, 21, 22, 23 and 24, which are preferably made of non-reflecting material. The strips just mentioned are arranged, so that the strip 18 is the shortest 75 and each of the strips gradually increase in length, so that the strip 24 is the longest. The strips also vary in width. The strip 18, which is the inner one, is the widest, while the strip 24, the outer one, is the narrowest. 80

The strips are curved from end to end and have their ends spaced apart, so that each strip forms an incomplete circle.

When all of the strips are mounted on the 85 wires 17, then an open portion is left between a pair of the wires 17. When three wires are used, which divides the circle or area contained within the ring 15 into six parts, then one-sixth of the area is left open, the purpose of which will be hereafter more fully set forth.

The strips 18 to 24 inclusive are inclined 90 downwardly from rear to front as shown in Figure 1. In order to accomplish this, I provide a spring clip 29, which is extended 95 around the ring 15 and which is provided with an inwardly, extending portion 30, having a hook 31 formed on its end. Instead of securing the lower ends of the wires 17 100 to the band 15, I secure them to the hooks 31, which causes the wires to be inclined or set at an angle. The mounting of the strips on the wires so arranged causes them to be inclined as mentioned.

Any rays of light from the lamp bulb 12, which are shot forwardly against the reflector 11, are then shot forwardly through the open surface formed through the open upper portion, which is left, due to the strips 110 forming an incomplete circle.

Any of the rays of light, which would or-

dinarily be shot forwardly or up into the air from the lower part of the reflector, are now shot against the under surface of the strips of non-reflecting material, thus preventing any rays from being shot upwardly. The rays of light, directed downwardly, are permitted to pass forwardly and downwardly upon the road, as desired.

It will be seen that the strips of material 10 restrict the undesired rays of light and yet permit all the light, which ordinarily goes upon the road to be projected on the road.

I have shown the strips having their forward ends doubled, so as to form a reinforcement.

The advantage of my device is that I am able to readily and easily install the light deflector and that it may be received between the lens and the reflector of the light. This 20 makes it possible to install my invention upon many of the lights now in use, without any rearrangement thereof.

Another advantage resides in the fact that all of the light rays from the upper portion 25 of the lamp are shot directly forwardly, while the light rays, which ordinarily are shot upwardly are restricted by the series of

strips, that I use, and all the light rays, which are shot directly forwardly from the lower half of the reflector are permitted to 30 pass between the strips without any interference.

Some changes may be made in the arrangement and construction of the various parts 35 of my improved device, without departing from the essential features and purposes of my invention, and it is my intention to cover by my claim, any modified forms of structure or use of mechanical equivalents, which may be reasonably included within its scope. 40

I claim as my invention:

In a light ray directing device, a series of curved strips bent to form partial cylinders arranged concentrically with the cylinders successively shorter from the inner to the outer one, radially arranged wires on which 45 said strips are mounted, an annular band, one wire being pivoted to part of said band and spring clips connected with said wires for supporting them on said band with the 50 strips tilted from the horizontal, substantially as shown.

Des Moines, Iowa, September 19, 1921.
CLAUDE E. MENTZER.
